COMBINED VISOR AND A PAIR OF SPECTACLES

William C. Moeller, Kansas City, Mo., assignor to Parmelee Plastics Company, Kansas City, Mo., a corporation of Missouri

Application October 13, 1958, Serial No. 52,945

Term of patent 14 years

(Cl. D57—1)

Fig. 1 is a front elevational view of a combined visor and a pair of spectacles, showing my new design.

Fig. 2 is a back elevational view thereof.

Fig. 3 is a top plan view thereof.

Fig. 4 is an end elevational view thereof; and

Fig. 5 is a cross sectional view thereof taken on line 5—5 of Fig. 1.

The dominant features of my design reside in the portions shown in full lines.

The temples are shown broken away in Figs. 3 and 5 for convenience of illustration.

I claim:

The ornamental design for a combined visor and a pair of spectacles, as shown and described.
